UNITED STATES PATENT OFFICE.

FRANK P. VINCENT, OF ELYRIA, OHIO, ASSIGNOR, BY MESNE ASSIGNMENTS, TO STEEL AND TUBES, INC., OF CLEVELAND, OHIO, A CORPORATION OF OHIO.

METHOD OF FORMING HOLLOW ARTICLES.

Application filed August 18, 1922. Serial No. 582,588.

My invention relates to the process for forming oval structural high-carbon steel tubes, and particularly to such processes as will enable one to manufacture tubes of this 5 character from sheet steel containing a high percentage of carbon which is rolled into tubular form, and thereafter caused to take the shape of an oval tube, the diameter of which is preferably increased in at least one 10 direction at some particular point intermediate the ends of the tube.

An object of my present invention is to provide a process whereby such tubes after being rolled may be brazed, and then when 15 so brazed so as to make a substantially oval tube, to subject the tube to pressure in a press in such a way that undesirable inequalities in the form of the brazed tube will be eliminated, and the tube will be given, if desired, 20 an irregular oval form, the tube being, as has been before stated, preferably of high carbon steel.

Another object of my invention is to provide an improved process for producing a 25 tube so formed that it will have the maximum of rigidity at an intermediate portion so that they will be highly efficient for the purpose of forming portions of structures such as bed spring side frame members and 30 the like.

Another object of my invention is to provide a process for forming the tube having a general oval cross sectional shape with ends which are substantially circular, when this 35 is desired, for the purpose of fitting attaching brackets having circular openings to the ends of the tubes, such, as for instance, bed spring side frame member end brackets.

My invention will be better understood by 40 reference to the accompanying drawing which shows apparatus for carrying out the process of my invention.

Referring to the drawings—

Fig. 1 shows a front elevational view of a 45 machine adapted to carry out my invention.

Fig. 2 shows a side elevational view of the machine illustrated in Fig. 1.

Fig. 3 shows a plan view of a tube formed in accordance with my invention.

Fig. 4 is a similar view of the same tube as shown in Fig. 3 except that the view is taken from a point at right angles to that of Fig. 3.

Figure 5 is an end elevation of the tube of Figures 3 and 4.

Fig. 6 shows a plan view of a modified form

of the tube formed in accordance with another embodiment of my invention.

Fig. 7 shows a plan view of the tube of Fig. 6 taken from the point at right angles to that of Fig. 6.

Figure 8 is an end elevation of the tube of Figures 6 and 7.

Fig. 9 shows a perspective view of the die plates employed to compress the tube ends of the oval tubes of Figs. 6 and 7 into substantially circular cross sectional shape.

Figures 10, 11, 12, and 13 are transverse sections of the tubes of Figs. 4 to 8, taken, respectively, on lines 10—10, 11—11, 12—12, and 13—13 of Figures 4 and 6.

Referring now to the drawings in all of which like reference characters indicate like parts, at 1, I show the frame of a press adaptable for use in carrying out my invention. At 2, I show a lower jaw for the said press rigidly mounted therein, and at 3, I show a reciprocating upper jaw for the press, at 4 I show a forming die mounted on the upper surface of the lower jaw 2, and at 5 I show an upper forming die member secured to the upper or reciprocating press jaw on its underside, the two forming dies presenting their forming faces toward each other, and in the forming faces of each I provide longitudinally extending grooves 6 for the lower die, and 7 for the upper die, these grooves are preferably of uniform cross-section throughout the length of the die, the surface of each groove being a cylindrical surface of less than 180° extent.

The grooves 6 and 7, when the dies 4 and 5 are brought nearly, but preferably not quite, together by downward movement of the upper reciprocating jaw carrying the upper die, defines an approximately oval opening 95 extending the full length of the dies, the opening, however, being preferably normally symmetrical with regard to lateral cross sections throughout its length, the opening comprising opposing portions each constituting 100 something less than a half circle, such portions being brought nearly together. The opening under such conditions will also correspond closely to the outside dimensions of the brazed tubes to be operated upon, although there will be a slight difference in that the vertical dimension of the opening under such a condition would be slightly less than such outside dimensions.

The material for the tubes is rolled into 110

sheets of high carbon steel of the requisite thickness and width, being rolled into tubular form, the rolling giving the tubes a form substantially cylindrical, the diameter of the 5 cylindrical tubes thus prepared being such that the tube when flattened to make it take the desired oval shape as described in connection with the latter steps of the process employed, will produce a tube having the requisite major and minor cross-sectional axes 10 dimensions.

The seams of the tubes thus prepared are now brazed, or the edges at the seam secured together in any other suitable way, but I prefer 15 to braze such a seam, it not being necessary for the purpose for which I use such tubes, to make a fluid tight seam, it only being essential for the purposes for which my tubes are intended to secure a strong joint 20 not a tight joint necessarily, although my invention might be employed in connection with such structures where a tight joint might be desirable. The tubes may be cut to length either before or after brazing, but I prefer 25 to cut them to length before the brazing.

The brazed tubes, substantially of cylindrical shape and of proper length, are now introduced into the press having the die plates 4 and 5 as before described, the cylindrical tube being placed in the groove 6 for 30 the lower die plate.

Now, prior to the operation of the press, and before the press is used to form these tubes of proper irregular oval shape, and 35 preferably when the lower die plate 4 is being positioned on the jaw 2, I place preferably between the die plate 4 and the lower jaw 2, near the ends of the jaw such as at 10 and 11, sheets of paper or like equivalent material 40 for the purpose, of proper thickness such as paper having a thickness of .008 inches, so that the lower die plate is supported at either end on the paper sheets and secured to the lower jaw 2 with the paper sheets near the 45 ends of the jaw, and between the die and the jaw.

The cylindrical tube now being positioned as before described in the groove in the lowermost die plate, the operator by operating the 50 press as by stepping on the pedal lever 8 will cause power from the motor 9 operating through suitable gears to cause the jaw 3 to descend vertically to such a distance that the tube will be pressed between the upper and 55 lower die grooves to such an extent that the pressure will cause the lower die plate 4 and to a lesser extent, the upper die plate 5, to yield slightly at their intermediate portions so that the pressure on the intermediate portion of the tube will be relieved relative to the pressures at the ends of the tube, and the 60 difference in pressures will be gradual, lessening from the ends of the tube towards the center of the tube.

65 I find that a tube so formed is wider in the

direction of its minor axis at the middle portion than it is at the ends, though not so wide in the direction of its major axis, and that it is possible to secure tubes of desired proper form having an enlarged central portion 70 which will be uniform, there being a practically negligible loss due to "culls" which under previously known processes for making oval tubes from steel of this character, has been very serious, which loss is now practically eliminated.

Such tubes, as shown in Figs. 3 and 4, may be used as bed spring side frame members, since due to their form whereby the thickness is greater at their intermediate portions, 80 they resist bending, and especially twisting stresses such as are incidental to the use of such side frame members in practice; these side frame members may be suitably attached to the end frame members of a bed spring, such end frame members being of angle iron or other forms, in any desired way, as by forming flanges on the ends of the tubes, or by brackets having tube end receiving sockets 85 and attaching flanges.

In Figs. 6 to 8 inclusive, I illustrate a different form of irregular oval tube which may be produced by my invention. In this embodiment of my invention, after the tube has 90 passed through the processes as before described, the ends of the tubes are inserted between die plates 12 and 13, Fig. 9, for a short distance, and the die plates are then brought together to compress the tube, the tube being so inserted that its major axis is in substantially a vertical plane, the co-operating grooves 14 and 15 which compress the ends of the tubes 16 and 17, Figs. 6, 7 and 8, are of substantially semi-circular cross sectional shape, and when brought nearly together, define a cylindrical opening, and compress the tube ends into substantially cylindrical shape.

This is of special advantage where it is desired to employ the oval form of tubes for 100 rigidity in constructions such as bed spring side frame members where the brackets for connecting the side member oval tubes, as produced by my invention, to the bed spring frames, such brackets commonly having 105 cylindrical shaped sockets adapted to receive the commonly employed cylindrical tubular bed spring side frame members.

Having thus described my invention as it 110 may be practiced in varying ways, I wish it to be understood that other forms of tubes than those specifically illustrated are contemplated in my invention, and that my invention is not limited to the precise means and methods herein illustrated and described, but the 115 spirit of my invention may be had in structures departing widely therefrom.

I claim—

1. The method of forming a hollow article 120 having a varying cross sectional configura- 130

tion which comprises simultaneously applying to an article of uniform cross section distorting pressures of varying amounts.

2. The method of forming a hollow metal article having varying cross sectional configurations which comprises applying to an article having a uniform cross sectional configuration, simultaneously and transversely at different parts of the article distorting pressures of varying amounts.

3. The method of forming a hollow metal article having varying cross sectional configurations which comprises simultaneously and transversely applying to an article of uniform cross sectional configuration distorting pressures of varying amounts throughout substantially the entire length of the article.

4. The method of forming a hollow metal article having varying cross sectional configurations which comprises simultaneously and transversely applying to an article of uniform cross sectional configuration distorting pressures of progressively varying amounts.

5. The method of forming a hollow metal article having varying cross sectional configurations which comprises applying simultaneously and transversely to an article of uniform cross sectional configuration distorting pressures of amounts varying progressively from the ends to an intermediate point of the article.

6. The method of forming a hollow metal article having varying cross sectional configurations which comprises placing an article having uniform cross sectional configurations between two relatively movable dies, moving the dies towards each other under sufficient force to deform the article, and allowing portions of one die to yield more than other portions.

7. The method of forming a hollow metal article having varying cross sectional configurations which comprises placing an article having a uniform cross sectional configuration between relatively movable dies, advancing the dies towards each other under sufficient force to deform the tube, permitting portions of one die to yield away from the other upon the application of said force, the extent of such yielding being sufficient to vary the cross sectional configuration of the finished article as desired, and varying progressively from a point of minimum to a point of maximum yielding.

8. The method of forming a hollow article having a varying cross sectional configuration, which comprises simultaneously applying to the article distorting pressures of varying amounts.

9. The method of forming a hollow metal article having varying cross sectional configurations, which comprises applying to the article simultaneously and transversely thereof, distorting pressures of varying amounts throughout substantially the entire length of the article.

10. The method of forming a hollow metal article having varying cross-sectional configurations, which comprises applying to the article simultaneously distorting pressures of progressively varying amounts.

11. The method of forming a hollow metal article having varying cross-sectional configurations, which comprises applying simultaneously and transversely to the article distorting pressures of amounts varying progressively from the ends to an intermediate point of the article.

In witness whereof, I have hereunto signed my name this 15th day of August, 1922.

FRANK P. VINCENT.
